 strom, Gary, Ind.

Application October 31, 1944, Serial No. 561,224

3 Claims. (Cl. 81—3.46)

1

This invention relates to a device for lifting covers on containers and the like.

The invention has as one object the provision of a tool by use of which pressed or driven-in covers for openings in containers and the like may be easily lifted.

A further object is the construction of such tool which removes covers without materially deforming the cover or the object such as a container to which the cover is affixed.

These and further objects of the invention will be more readily apparent during the course of the following description.

In the shipment of many different kinds of materials, whether dry or liquid, there are employed containers provided with pressed or driven-in covers. Such covers are difficult to remove, particularly if they are of the snap lid type, without seriously deforming the cover, the container, or both. Such deformation is undesirable because it renders the cover or the container unfit for reuse. Furthermore, in the case of materials which are explosive per se or which generate explosive fumes, it is obviously dangerous to hammer or pry indiscriminately the container or the cover in removing the latter, both by reason of the jarring of the material and the possibility that a spark may be struck by such procedure.

The tool of the present invention allows the safe, sure lifting of covers of the type described having upstanding rims without any material deformation of the container or cover, and without any jarring of the contents, by providing means for positively clamping a portion of the upper edge of the cover between an abutment and a movable clamping member and then effecting lifting of the cover in the clamped portion by pivoting it about a point or points remote from the clamped portion. The invention will be more readily understood by reference to the accompanying drawings, in which:

Figure 1 is a view in elevation of one embodiment of the tool of the present invention;

Figure 2 is a plan view of the tool shown in Figure 1;

Figure 3 is a view partly in vertical section of the tool shown in Figures 1 and 2 in operative relationship to a beaded rim cover to be lifted;

Figure 4 is a view partly in vertical section of another embodiment of the tool in operative relationship to a flared rim cover;

Figure 5 is a view partly in vertical section of the tool shown in Figures 1 and 2 in the position it assumes immediately after its placement in the cover;

2

Figure 6 is a similar view of the tool shown in Figures 1 and 2 after the rim engaging hook has been placed in confronting relationship with the beaded rim on the cover; and

Figure 7 is a view similar to Figure 6 but showing the cover partially removed from the can.

The cover lifter of the present invention shown in Figures 1, 2, 3, 5, and 6 is particularly adapted for the lifting of covers having beaded upstanding rims, as shown in Figure 3. The cover 2 shown in that figure in position on can 1 is of the snap lid type, that is, it has an enlarged portion 19 near the bottom thereof, such portion being of slightly greater diameter than the opening in the can, so that when the cover is pressed into such opening, it snaps into place and is retained by the enlarged lower portion of the cover. It is to be understood, however, that the tool is useful in lifting other pressed or driven-in covers, such as those having generally conical outer surfaces cooperating with conical surfaces in the opening in the container to effect a seal.

The tool shown in Figures 1 and 2 consists of a base plate 3 of extensive area, which is adapted to rest upon the broad inner upper surface of the cover. In the embodiment illustrated, plate 3 is made of such size and shape that it fits fairly closely within the edges of the broad upper surface of the cover. Attached to the upper surface 30 of plate 3, as by being welded thereto, is an upstanding bifurcated bracket 4. In the tool shown, bracket 4 is positioned at the center of plate 3, but it is obvious that it may be located on such plate a considerable distance either way 35 of the center. Supported on bracket 4 for pivotal movement in a plane at right angles to the plate is a lever designated generally by the reference character 5. Lever 5 is provided with a downwardly extending bracket 6 having the lower end 40 thereof in the form of a link fitting within the ears of bracket 4 and connected thereto by pin 7. The long portion of the lever 5 to the right of pivot pin 7 in Figures 1 and 2 constitutes an operating handle 8, whereas the short end 9 of the lever, to the left of the pivot pin, constitutes the means for supporting and operating clamping member 10 which is pivoted thereto by pin 11 so that it may move freely in the plane of movement of lever 5.

50 The outer end of clamping member 10 is provided with a generally downwardly extending end 12 in the form of a hook, the end of which points back toward upstanding curb member 13, with which plate 3 is provided at the edge confronting hook 12. Curb member 13 stands gen-

erally at right angles to the base plate, and is shaped to conform to a segment of the cover to be lifted. In the tool shown, curb 13 has a cylindrical curve laterally, since the tool is to be used in lifting round covers. The tool is further provided with an inclined ramp 14, which may be made of sheet metal, which extends upwardly from bracket 4 over the top of curb 13 to form an overhang or lip 15. Ramp 14 may be welded in place to the base plate and to the curb. In order that the tool may be placed on the cover to be lifted without the exercise of too much care to avoid mechanical shock, and in order to minimize the danger of striking sparks when the tool is operated, the bottom surface of plate 3 is provided with a gasket 16, which may be made of an elastomer, such as rubber, synthetic rubber, or the like, or of other electrically insulating mechanical shock absorbing substances such as fiber.

The curb 13 may be made of such height that the bottom surface of lip 15 rests upon the upper edge of bead 17 of the cover when gasket 16 rests upon the inner surface of the cover at a point beneath the curb. However, to allow the tool to function properly in spite of variations in the height of the cover edge, from cover to cover, the curb is usually made of such height that when lip 15 rests upon the bead 17 of an average cover there is a small clearance, shown at 21 in Figure 3, between the gasket 16 and the cover at a point beneath the curb.

The tool described is utilized in the following manner. Base plate 3 is placed within the cover as shown in Figures 3, 5, and 6, so that curb 13 abuts one inner portion of the upstanding edge of the cover, and the bottom surface of lip 15 contacts the upper edge of the cover. In Figures 3, 5, and 6 the tool is shown within the cover in substantially the above described position, curb 13 being shown, however, for the sake of clarity, spaced slightly from the inner surface of the upstanding edge of the cover. Arm 8 of lever 5 is held in depressed position, when the tool is being so located on the cover, with the freely pivoted clamping member 10 positioned with hook end 12 lying upon an intermediate portion of the ramp 14. After the tool has been positioned relative to the cover, arm 8 of lever 5 is raised to depress the outer end of arm 9 and thus slide hook 12 up the ramp and over the end of lip 15. Movement of arm 8 in the downward direction then brings the pointed end of hook 12 under bead 17 of the cover and between it and the upper edge of the upstanding edge of the cover opening in can 1. Figures 5, 6, and 3 of the drawing, taken in that order, show the above describing sequence of operations. In Figure 5 the tool is shown as it appears just after having been placed within the cover. As shown, the bottom surface of the hook 12 then rests upon ramp 14. Upon raising handle 8 to the position shown in Figure 6 the hook 12 rides over the lip 15 at the forward end of the ramp 14 and falls freely until the inner surface of hook 12 contacts lip 15. Downward movement of handle 8 after the hook has so fallen then brings it into clamping contact with rim 17 of the cover, as indicated in Figures 1 and 2 and as shown on a larger scale in Figure 3.

As above explained, in the drawings curb 13 is shown spaced somewhat from the inner surface of the upstanding rim of the cover. In actual use, however, the curb abuts such inner surface of the rim and the bead 17 is subjected

to a positive clamping action between hook 12, lip 15, and curb 13, the forces exerted by such members being illustrated in Figure 3 by the arrows designated *a*, *b*, and *c*, respectively. Further movement of arm 8 serves to clamp the bead of the cover more tightly, and finally to tend to pivot the entire lifting tool about the heel 20 of base plate 3. The cover is thus lifted progressively from the portion clamped by the tool, pivoting about a point or points adjacent heel 20 of the base plate and remote from the point clamped by the tool. Since the clamping of the bead on the cover is done between members which conform at least approximately to the shape of the bead and which initially contact such bead, little if any deformation of the cover occurs at such point. Since the base plate of the tool is of extensive area, it distributes the forces exerted over substantially the entire cover, thus preventing bending of the cover at other places.

The tool of the present invention may also be employed to lift covers having upstanding flared rims. In Figure 4, a can 22 having a cover 23 with a flared rim 24 thereon is shown. In this instance, the opening in the container top is provided with a downwardly and inwardly turned rim 25 against which the flared rim 24 of the cover is pressed. The tool for lifting such cover has the same general arrangement as that shown in Figures 1 and 2. In this instance, however, the curb 26 is formed with an upper outwardly curved edge conforming at least approximately to the shape of the upper portion of the flared rim 24 of the cover. Such curb is likewise of a shape, laterally, to conform to a segment of the cover to be lifted. A ramp 27 is welded to curb 26 as shown, and has the same function of guiding the hook end of the movable clamping member 10 up over the lip of the curb. The upper portion of curb 26 in this instance, however, forms the overhanging lip. Since there is but slight clearance between the top of the can and the flared rim of the cover, when the latter is in place, the hook-like end 28 on member 10 is formed with a relatively long sharp point for penetration into such space. Hook member 28, when advanced into clamping position by downward movement of the operating handle, positively clamps the upper edge of the flared rim between it and the overhanging lip portion of curb 26. The clamping forces to which the rim is subjected are illustrated by the arrows *d* and *e*, in Figure 4. The flared rim cover is lifted after one portion has been clamped, as shown in Figure 4, in the same manner as a bead rim cover; that is, the operating handle is further depressed, the base plate pivots about the heel, the cover pivots about a point or points remote from the portion clamped and the cover is progressively lifted beginning at the position at which it is clamped.

As shown in Figure 4, curb 26 may be made of such height as to provide, with an average cover, a clearance 29 between the bottom of the gasket 16 and the inner top surface of the cover when the upper lip portion of the curb is in contact with the top of the flared rim of the cover. Here again, however, such clearance may be eliminated if the edges of the covers to be lifted are sufficiently uniform in height so that the gasket will contact the cover and the lip will contact the rim in all cases.

Having thus fully disclosed our improved cover lifter, we desire to claim as new the following:

1. A cover lifter comprising a base member of extensive area adapted to fit within the top of a cover of a type having an upstanding rim, the top edge of which is outturned, said base member having an abutment projecting upwardly from one edge thereof, said abutment being disposed generally at right angles to the base member and conforming generally to a segment of the edge of the cover to be lifted, said base member extending from said abutment to a point near the diametrically opposite edge of said cover, a lever pivoted intermediate its length to the upper side of the base member for movement in a plane at right angles to the base member, the end of said lever adjacent the abutment carrying a clamping member pivoted thereto for movement in the plane of movement of the lever, the outer end of the clamping member being formed in the shape of a generally downwardly extending pointed hook, said hook being inturned toward and cooperating with the abutment when the latter is positioned adjacent the inner edge of the cover to grip the upper portion of the cover edge between the hook and the abutment.

2. A cover lifter comprising a base member of extensive area adapted to fit within the top of a cover of a type having an upstanding rim provided with an outturned upper edge, said base member having an abutment on one edge thereof disposed generally at right angles to the base member and conforming generally to a segment of the edge of the cover to be lifted, a lever pivoted intermediate its length to the base member for movement in a plane at right angles to the base member, one end of said lever constituting an operating handle and the other end carrying a clamping member freely pivoted thereto for movement in the plane of movement of the lever, the outer end of the clamping member being formed in the shape of a generally downwardly pointed hook inturned toward the abutment, an inclined ramp member attached to the upper portion of the abutment, the hook on the clamping member resting on the ramp when the operating handle of the lever is in a depressed position adjacent the base, said hook being guided up the ramp and over the upper portion of the cover edge, when the abutment is positioned adjacent the inner edge of the cover, upon movement of the handle end of the lever away from the base, said hook cooperating with the abutment to grip such outturned upper

edge of the cover between them when the handle of the lever is moved toward the base member.

3. A cover lifter comprising a base member adapted to fit within the top of a cover of a type having an upstanding rim provided with an outturned upper edge, a lever pivoted intermediate its length to the base member for movement in a plane at right angles to the base member, one end of said lever constituting an operating handle and the other end carrying a clamping member freely pivoted thereto for movement in the plane of movement of the lever, the outer end of the clamping member being formed in the shape of a generally downwardly extending pointed hook inturned toward the abutment, said base member having an abutment on one edge thereof, said abutment being disposed generally at right angles to the base member, an inclined ramp member attached to the upper portion of the abutment and having a portion overhanging the outer edge of the abutment to form a lip, the hook on the clamping member resting on the ramp when the operating handle of the lever is in a depressed position adjacent the base, the hook of the clamping member being guided up the ramp and over the lip of the abutment and the upper portion of the cover edge when the abutment is positioned adjacent the inner edge of the cover, upon movement of the handle end of the lever away from the base, said hook cooperating with the abutment to grip the outturned upper edge of the cover between them when the handle of the lever is moved toward the base member.
